UNITED STATES PATENT OFFICE.

MOSES MOSLER, OF NEW YORK, N. Y., AND CARL BARTELS, OF HAMILTON, OHIO,
ASSIGNORS TO THE MOSLER SAFE COMPANY, OF NEW YORK, N. Y.

SAFE.

1,399,512.

Specification of Letters Patent.

Patented Dec. 6, 1921.

Application filed September 22, 1919. Serial No. 325,573.

To all whom it may concern:

Be it known that we, MOSES MOSLER and CARL BARTELS, citizens of the United States, and residents of New York, New York county, New York, and Hamilton, Butler county, Ohio, respectively, have invented certain new and useful Improvements in Safes, of which the following is a specification.

10 This invention pertains to improvements in safes, and particularly to that class of semi-fireproof safes generally spoken of as safe cabinets or cabinet safes, and the improvements will be readily understood from 15 the following description taken in connection with the accompanying drawing in which:—

Figure 1 is a plan of a safe cabinet embodying an exemplification of our invention, 20 a portion appearing in horizontal section in the plane of line *a* of Fig. 2:

Fig. 2 a vertical section of a portion of the structure in the plane of line *b* of Fig. 1; and

25 Fig. 3 an end elevation of one of the removable shelves. A variety of scales is employed in the drawing.

In the drawing:—

1, indicates the exterior metallic shell of 30 the cabinet:

2, the doors:

3, the lining forming the inner wall of the cabinet:

4, a lining secured against the inner surface of the side of the inner lining 3 and corrugated into ratchet form presenting upwardly facing shoulders:

5, a similar lining against the inner surface of the back of the inner compartment:

40 6, a similar corrugated lining secured against the ceiling of the inner compartment:

7, air spaces formed between the lining 3 and the inner lining:

45 8, a removable metallic shelf, of which there may be any desired number, disposed removably in the inner compartment and supported by the upwardly presenting shoulders of the lining 4:

50 9, a roll on the forward edge of shelf 8 to give vertical stiffness at the unsupported edge of the shelf; and 10, upwardly presenting grooves which may be provided in shelf

8, these grooves being spaced apart the same as the teeth of roof-lining 6.

55

The shell 1, and its lining 3, and the doors 2, may be formed as usual, and the space between the shell and the lining may, if desired, be filled with a selected non-conductor of heat, and the doors may, as is usual, be 60 constructed hollow, of sheet metal.

The corrugated inner linings 4, 5 and 6, may be secured to the walls of the inner compartment by means of spot welding. The toothing of the inner lining gives support to the ends and to the rear edge of the shelf, and the shelf may be put in selected position on the upwardly presenting surface of any one of the corrugations. Articles placed on the shelf or shelves are kept away 70

from the wall of the inner compartment by the corrugated members, the spaces 7 forming an insulation between the double walls of the inner compartment. By placing the shelf 8 but a few corrugations down from the roof of the inner compartment, pigeon holes may be formed by means of removable partitions inserted between the shelf and the roof of the inner compartment, the corrugations below the roof of the inner compartment serving to space such partitions, which partitions engage in the roof corrugations and in the grooves 10 if the shelf be supplied with them.

75 We claim:—

In a safe, the combination of a lining member, a corrugated inner lining secured against the inner vertical surfaces of said lining member, to present aligned horizontal shoulders on opposite sides, a corrugated lining secured to the ceiling of said lining member, to present vertical shoulders, and a shelf adapted to rest on said horizontal shoulders and having vertical grooves, adapted to receive the bottom edges of partitions having their upper edges engage said vertical shoulders.
